HANDLE

Jack B. Stuman, Rockford, Ill., assignor to Geo. D. Roper Corporation, Rockford, Ill., a corporation of Illinois

Application January 2, 1951, Serial No. 13,642

Term of patent 14 years

(CL. D10—8)

To all whom it may concern:

Be it known that I, Jack B. Stuman, a citizen of the United States, residing at Rockford, in the county of Winnebago and State of Illinois, have invented a new, original, and ornamental Design for a Handle, of which the following is a specification, reference being had to the accompanying drawings, forming part thereof.

In the drawings:

Fig. 1 is a perspective view of a handle embodying my new design;

Fig. 2 is a front elevational view thereof;

Fig. 3 is a side elevation thereof;

Fig. 4 is a back view of the handle;

Fig. 5 is an end view with the knob portion of the handle removed below the line 5—5 (Fig. 2), in order to better indicate the knob shape; and

Fig. 6 is an end view of the handle.

The characteristic features of the design reside in the portions shown in full lines.

I claim:

The ornamental design for a handle, substantially as shown and described.

JACK B. STUMAN.
